NOZZLE MATERIAL FIRING EVALUATION MEANS AND SYSTEM

Harry Wolff, Los Gatos, Calif., assignor to the United States of America as represented by the Secretary of the Air Force

Filed July 18, 1963, Ser. No. 296,146
4 Claims. (Cl. 73—116)

This invention relates to testing and evaluating means, and more particularly, to a system and means for evaluating nozzle material for rocket type motors and similar devices.

The evaluation of nozzle material for jet and rocket propulsion devices is a relative procedure wherein the performance of a sample material is compared to a known standard. In practice, materials are frequently evaluated as a nozzle insert in a solid propellant test motor fired at specific chamber pressures and durations. Efforts have been made to minimize firing to firing variations and maintain identical test conditions necessary for satisfactory evaluation, but these goals are not frequently met. The major difficulty lies in repeating the test chamber pressure time history exactly since ablation characteristics of different types of materials are not uniform and the resulting change in nozzle throat area also affects the solid propellant motor chamber pressure. Variation in chamber pressure is, in effect, a continuous change in test conditions that complicates and, in fact, prevents effective exact comparison of a sample material with a known standard material, for instance, the material used in the nozzles or nozzle inserts of jet and rocket motors, and the like.

Efforts have also been made with gaseous oxygen-gaseous hydrogen propellant test motors both with and without the addition of substances intended to simulate the combustion products of solid propellants. These devices provide the time necessary for sufficient ablation of a nozzle insert to reduce chamber pressure to a predetermined level at which time the test is terminated. However, simulated combustion products obtained by these propellants do not match solid propellant exhaust products and pose technical difficulties in metering various solid additives to the basic gaseous propellants.

The present invention eliminates the above-mentioned difficulties and objections by providing a simple self-contained unit which provides pressure time conditions over the full duration of the test. Solid propellant is employed to provide correct exhaust products with no problems of valving and metering of gaseous propellants or additives.

An object of the invention is to provide a direct means for comparing a sample material, such as used in a nozzle or nozzle insert in a jet motor against a known standard material for the same purpose under identical test conditions for the full test duration.

A further object of this invention is the provision of a testing device for material which goes into the manufacture of rockets and jet motors and is subject to some ablation due to heat and pressure, in which a sample of the material is simultaneously subjected to the same identical conditions of heat and pressure during a full time duration of test with a standard known material to establish an accurate comparison of the performance of the sample material with the standard material, in which a wide variety of heat and pressure conditions may be provided.

A further object is the provision of simple means for comparing a sample exhaust nozzle insert simultaneously with a similar standard nozzle insert under identical pressure and identical time durations in which pressure and

heat are supplied simultaneously from a solid fuel propellant.

More particularly, a further object is the provision of a solid fuel propellant combustion chamber having means at one end for receiving a standard exhaust nozzle made of a known standard material and means at the opposite end of the combustion chamber for receiving a similar exhaust nozzle made of a test material to be evaluated, tested and compared with the aforesaid known sample, including means for inserting and firing a solid propellant in said combustion chamber, whereby both exhaust nozzles are subjected to identical propellant pressure, heat and duration conditions to provide an accurate comparison between the nozzles and the material therein under identical conditions of test.

A further object is the provision of a device having an elongated cylindrical combustion chamber having identical removable nozzle assembly ends for receiving a solid propellant therebetween, and means in each of said 20 receivable ends for removably receiving an identical rocket type exhaust nozzle insert therein, whereby a nozzle insert of standard known material can be inserted in one of said assembly ends and an identical sample nozzle insert made of a material to be compared with the 25 standard material of the other nozzle can be inserted in the opposite end nozzle assembly and compared for ablation, when a solid fuel propellant is inserted in said combustion chamber between the nozzles and ignited.

A further object includes a construction just mentioned, 30 including means for indicating combustion chamber pressure throughout the duration of combustion of the propellant in the combustion chamber.

Other objects and advantages of the invention will become apparent from the following description and accompanying drawing which illustrates a side view of the testing device of the invention with the upper half broken away and shown in section, and also with the combustion chamber broken away intermediate its ends and foreshortened.

40 Referring to the drawing, the reference numeral 1 denotes a cylindrical combustion chamber supported horizontally intermediate its ends by a support bracket 2. The opposite ends of the combustion chamber are identical and terminate in enlarged head members 3 and 4, each formed with internal cylindrical bores 3a and 4a for receiving the nozzle insert holding assemblies 5 and 6.

45 These assemblies 5 and 6 are identical and, therefore, the same reference numerals will be used in connection with the parts thereof, except that one of the assemblies, 50 for instance the assembly 6, will be denoted mostly by primed reference numerals while the assembly 5 will not employ primed reference numerals.

The assemblies 5 and 6 comprise tubular flanged inserts 7—7' fitting the recesses 3a and 4a respectively and being removably retained therein against the faces 3b and 4b by the annular split snap rings 8 and 8' seated in the grooves or internal annular channels 9 and 9'.

55 In the periphery of each flange portion is an annular recess 10—10' having a conventional O-ring therein, preventing leakage between the interior of the heads 3 and 4 and the flanged tubular members 7 and 7'.

The tubular members 7 and 7' are each threaded externally, as indicated at 11 and 11', and formed with end 60 shoulders 12—12'. The internal cylindrical bores 13—13' are dimensioned to receive identical test items, such as the respective socket nozzles or nozzle inserts 14 and 15. These nozzle inserts are identical in size and shape, each having an annular head portion 14a and 15a and a smaller 65 diameter extension 14b and 15b which fits the bores 13 or 13' in the members 7 and 7'.

The nozzle inserts 14 and 15 each have an annular

channel 14c and 15c in which is disposed an O-ring to prevent leakage between the exterior of the nozzle inserts 14 and 15 and the bores 13 and 13'.

The throats 16 and 16' of the nozzle inserts 14 and 15 are shown also identical and the inserts are retained in the nozzle assemblies by the internally threaded nozzle retainer members 17 and 18, threaded on the threaded portions 11 and 11' of the members 7 and 7'.

The outer faces 17a and 18a of the nozzle retainer members 17 and 18, carry nozzle insert retainer rings or apertured plates 19 and 19' which overhang the ends of the nozzle inserts for retaining the nozzle inserts 14 and 15 against the shoulders 12 and 12', preventing axial displacement of the nozzle inserts during operation of the device.

Removing one or both of the nozzle assemblies 5 or 6 permits the cylindrical chamber 1 to be loaded, for instance by solid propellant jet fuel, such as indicated at 20, which may be two one pound cartridge loaded propellant grains, with a separating spacer 20' therebetween to provide room for a central chamber pressure transducer tap 21 for a pressure transducer and pressure gauge 22, or recorder of conventional construction to measure or record the chamber pressure during the test operation of the device.

Chamber pressure achieved is a function of predetermined ballistic parameters and is identical throughout the combustion chamber 1 and in the throat sections of both nozzle inserts 14 and 15.

Ignition is simply achieved by any suitable means, such as a pyrotechnic bag igniter 23 placed on the grain 20 in the center of the motor and, in practice, the igniter is actuated electrically and the propellant grain is ignited.

As one or both of the throats 16-16' ablate, chamber pressure is reduced but it is always identical in both nozzle inserts throughout the effective burning time.

When a nozzle insert made of a standard known material and construction is inserted in one nozzle, assembly members 5 or 6 and a nozzle insert which is made of a different material or construction is inserted in the other nozzle assembly member for the purpose of comparing the behavior of the sample and the standard material nozzle, it is evident that during the duration of the test both materials will be subjected to identical test conditions.

The invention therefore provides a direct means for comparing a sample material against a standard material under identical heat and pressure test conditions for the full test duration, and the device may be employed with a wide variety of solid propellants to duplicate use conditions.

Also the device may be scaled to any size desired. Furthermore, the principle and method may be extended to provide evaluation of nozzle material for liquid, gaseous, hybrid, and slurry propellant systems.

Removal of the plates 19 and 19' by removal of the screws permits the nozzle inserts 14 and 15 to be removed from the nozzle assemblies 5 and 6, while removal of the snap rings 8 and 8' permits the flanged tubular member 7 and 7' to be removed from the combustion chamber heads 3 and 4, and also provides for loading the combustion chamber 1 with suitable predetermined propellants for a test.

The nozzle material evaluation test motor is, of course, rigidly mounted or bolted through the support bracket 2 to a suitable rigid support before making a test.

Although the invention has been described and illustrated in detail, it is to be clearly understood that the same is by way of illustration and example only, and is not to be taken by way of limitation, the spirit and scope of the invention being limited only by the terms of the appended claims.

I claim:

1. A rocket nozzle material evaluation test motor comprising an elongated cylindrical combustion chamber open

at its opposite ends, a rocket nozzle receiving assembly removably carried by each end of the combustion chamber shaped to receive a similarly shaped nozzle insert therein with said nozzle inserts facing in opposite directions concentric to the axis of the combustion chamber, means carried by each of said rocket assemblies for removably securing one of said rocket nozzle inserts therein against outward movement away from said combustion chamber, whereby when a propellant means is introduced in said combustion chamber and fired both of said nozzle inserts will be simultaneously subjected to identical heat, pressure and test duration conditions so as to compare the durability of one of said nozzle inserts in one of said nozzle assemblies with the other nozzle insert in the other nozzle assembly simultaneously under identical combustion pressure, heat and test duration conditions.

2. A device for the evaluation and comparison of a sample jet nozzle with a standard jet nozzle of similar configuration to simultaneously compare the relative ablation in the throat portion of the sample jet nozzle with the standard jet nozzle comprising, an elongated cylindrical combustion chamber having an enlarged cylindrical head portion at each end thereof, said head portions each having a similar cylindrical bore therein extending inwardly toward said combustion chamber concentric to the axis of said combustion chamber, a pair of similar jet nozzle holding assemblies each having an annular flange portion slidably fitting said bores, means between said head portions and assemblies for removably securing said assemblies in said bores, said jet nozzle assemblies each having a similar cylindrical extension adapted to extend outwardly away from said combustion chamber and dimensioned internally to receive one of said similar standard and sample jet nozzles therein, cylindrical concentric nozzle retaining means removably connected to each of said cylindrical extensions for retaining one of said jet nozzles in one of said assemblies at each end of said combustion chamber concentric to the axis thereof, said combustion chamber adapted to receive a solid fuel jet propellant therein between the ends thereof, and means for igniting said propellant, whereby the throat portions of both of said nozzles will be simultaneously subjected to identical heat, pressure and time duration conditions during the combustion of said solid propellant, to simultaneously compare the ablation of the material in the throat portions thereof.

3. A testing device for simultaneously testing and comparing the ablation of the material in a test jet nozzle with the material in a known standard similar jet nozzle under identical test conditions as set forth in claim 2, including pressure indicating means responsive to pressure within the combustion chamber throughout the duration of the combustion of a propellant when fired within said combustion chamber.

4. A testing and comparison device for comparing the ablation of material in a test sample jet nozzle with the ablation of material in a standard known similar jet nozzle simultaneously under identical heat, pressure and time duration conditions comprising, a cylindrical combustion chamber, separating spacer ring means therein substantially midway between the opposite ends of the combustion chamber, said combustion chamber adapted to receive cartridge loaded solid propellant means therein between said spacer means and each end of the combustion chamber, means for simultaneously igniting said propellant means, pressure indicating means connected to said combustion chamber adjacent said separating spacer for indicating pressure within said combustion chamber during the combustion of said solid propellant means, nozzle assembly means removably secured to the opposite ends of the combustion chamber for removably fixing a similar contoured jet nozzle, concentric to the axis of said combustion chamber, in sealed relation to said combustion chamber, with said nozzles extending outwardly away from the opposite ends of the combustion

chamber in axial alignment with each other, whereby when a test sample jet nozzle is fixed in one of said nozzle assembly means and a standard known jet nozzle is fixed in the other nozzle assembly means at the opposite end of the combustion chamber and the propellant cartridge loaded propellant means is ignited the ablation of the material in the throat portions of the test sample nozzle and the ablation of the material in the standard known nozzle at the opposite end of the combustion chamber are subjected to identical conditions of heat,

5 pressure and time duration and the relative ablation there-between can be determined.
